Application March 2 1942 Serial No. 321 822

This invention relates to testing machines for paint films and, more particularly, to a machine for determining the maturity of paint films in which a plurality of members are adapted to be applied to the surface of the paint film to mark such surface thus effacing to different degrees indicia placed thereon and indicating the degree of maturity of the paint film by comparison of such effaced indicia.

The chief object of my invention is to provide a machine for testing paint films, which can be economically produced and which readily, easily and accurately performs its intended purpose. An object of my invention is to provide a machine which readily determines the degree of maturity of paint films. Other objects of my invention will be readily perceived by reference to the following description of my invention.

This invention relates to a testing machine for paint films which comprises a plurality of weighted members adapted to mar to different degrees the surface of a paint film, and means for supporting the paint film in predetermined relationship to said members. More specifically, the invention relates to a machine for determining the degree of maturity of paint films which comprises a plurality of weighted members adapted to mar the surface of a paint film to efface to different degrees indicia placed thereon, and means for supporting a paint film carrying such indicia in predetermined relationship to said members.

The attached drawing illustrates a preferred embodiment of my invention, in which—

Figure 1 is a view in elevation of the testing machine of my invention:

Figure 2 is a plan view of the machine shown in Figure 1; and

Referring to the drawing, there is shown a frame consisting of a base 2, opposed vertical uprights 3, and a motor platform 4 mounted on one end of the base 2. On the opposite end of the base 2 are placed opposed uprights 5 for a purpose hereinafter described. Channel irons 6 extend longitudinally of the base 2 and form a track for a purpose hereinafter described. A plurality of horizontally extending arms 7 are pivoted on a shaft (not shown) held between the vertical uprights 3. Adjacent or at the end of each arm 7 is mounted a tip member 8, which may be in the form of a ball approximately $\frac{1}{4}$ " in diameter, adapted to engage the surface of a paint film.

It will be understood the members 8 may be in the form of knife edges or cones or the like, if desired, depending upon the degree of maturity of paint films to be tested or whether such films 5 are tested for hardness, toughness, resistance to tensile forces, or the like. At the upper end of the vertical uprights 3 are mounted horizontally, extending channel irons 9 secured on opposite sides of the machine. The irons 9 support trans- 10 versely extending spindles 10 on which are mounted a plurality of freely rotatable pulleys 11. Weights 12 are suspended from the pulleys 11 in any desired manner, for example, by means 15 of wires, ropes, or belts 13 which pass over the pulleys and are connected to the opposite ends of the pivoted arms 7. The weights 12 carry different loads and thus exert greater or less forces on the pivoted arms 7. Preferably, such weights 12 in the illustrated embodiment of my invention 20 range from two pounds to eight pounds. The weights 12 serve to hold one end of each of the pivoted arms 7 in raised position thus holding the opposite ends carrying the ball members 8 in lowered position in engagement with the surface 25 of a paint film.

Between the uprights 5 and adjacent the ends of pivoted arms 7 is mounted a cam member 14 journaled in the uprights 5; a handle 15 is connected to one end of the cam member 14. Preferably, the cam member 14 is so mounted that in its normal position it forces downwardly the ends of the pivoted arms 7 thus raising the opposite ends of the arms 7 carrying the ball members 8 and holding such members out of contact with a paint film. In other words, the cam member 14 serves to raise the ball members 8 against the force of the weights 12. When it is desired to move the ball members 8 into engagement with the surface of a paint film the cam member 14 is rotated by moving the handle 15 upwardly thus releasing the pivoted arms 7 and permitting the weights 12 to exert their forces on the arms 7.

A movable carriage 16 having wheels 17 travels on the track formed by the channel irons 6. A clamp 18 is provided at one end of the carriage 16 and serves to hold a paint film carried by a suitable base in fixed position on the carriage.

The carriage 16 is connected to a pulley 19 by means of a wire, rope or belt 20, the pulley 19 being mounted on a shaft 21 supported by a hanger 22 mounted on the motor platform 4, and carries on one end a bevel gear 23 adapted to mesh with a similar bevel gear 24 carried on the shaft 25 of a motor 26.

55 The degree of maturity of the so-called com-

paratively soft, dull coating paints may be determined in the following manner. A paint film 27 carried by a suitable base is placed on the carriage 16 in such manner that its grain extends laterally of the machine. Indicia 28, for example, parallel pencil lines, ten to thirteen in number, drawn with a medium soft graphite pencil, are drawn extending in a direction parallel to the direction of graining or, in other words, extending transversely of the carriage. The cam member 14 is actuated to release the pivoted arms 7 thus permitting the ball members 8 to engage the surface of the paint film 27. The motor 26 is then actuated to draw the carriage 16 beneath the ball members 8 at a predetermined speed, for example, about $2\frac{1}{2}$ " of travel per minute. In this manner, a paint film to be tested is drawn beneath the ball members 8 which bear with varying forces on the surface of the moving paint film 27 and which mar or disfigure the film surface by forming grooves or furrows 29 therein thus effacing to different degrees the indicia 28 drawn thereon. The degree of maturity of the paint film may be measured in terms of the weight or load required to efface at least 50% of such pencil lines.

In Figure 3, I have shown an enlarged view of a paint film tested in the above manner. Indicia 28 extend laterally of the film 27 while furrows 29, designated at A, B, C, D, E, F, and G, extend at right angles thereto. Weights of two to eight pounds were applied to the ball members 8 which formed the furrows A, B, C, D, E, F, and G, respectively; accordingly, the degree of maturity of the paint film 27 is approximately four and one-half pounds when compared with paint films similarly tested, since not quite 50% of the pencil lines were effaced by the furrow C formed by the member 8 supporting a load of four pounds while more than 50% of the lines were effaced by the furrow D formed by the ball member 8 supporting a load of five pounds. It will be seen this is a simple, accurate test which can be readily performed to determine, within reasonably close dimensions, the comparative degree of maturity of paint films.

It will be understood the test above described is not entirely satisfactory for determining the degree of maturity, hardness, toughness, or resistance to tensile forces of extremely hard or glossy paint films on which indicia 28, such as the pencil lines, cannot be satisfactorily placed. When it is desired to test extremely hard or glossy paint films, the weights 12 may be changed to apply suitable forces to the members 8 and the degree of maturity, hardness, toughness, resistance to tensile forces or the like is determined from a comparison of the furrows 29 formed in the paint film by the members 8 and the loads required to form such furrows. The shape of the members 8 may be changed, if desired, to form any other standardized type of marks or ruptures, the degree of maturity, hardness or resistance to tensile forces being determined by the comparison of such marks with one another and the weights required to form such comparative marks.

If desired, the motor 26 and mechanism connecting it to the carriage 16 may be eliminated and the carriage moved manually. I prefer, however, that the carriage be driven at a predetermined speed since more accurate comparative results are obtainable in the testing of paint films.

My invention provides a ready, accurate and

5 economical device for determining the degree of maturity of paint films. The device may be used to test comparatively soft, dull paint films or relatively harder, glossy paint films with accurate results even by comparatively unskilled operators and provides an economical and ready means for measuring the degree of maturity, toughness, hardness, or resistance to tensile forces of paint films.

10 While I have described and illustrated a preferred embodiment of my invention, it will be understood my invention is not so limited since it may be otherwise embodied within the scope of the following claims.

I claim:

15 1. In a testing machine for paint films, the combination of a frame, a plurality of separate, independent arms pivoted on said frame, ball members mounted on said arms adapted to mar to different degrees the surface of a paint film, a plurality of weights connected to the ends of said arms serving to hold the ball members in lowered position, a cam member mounted on said frame adjacent the ends of said arms serving to raise the ball members against the force of said 20 weights, and means for supporting a paint film in predetermined relationship to said ball members.

25 2. In a testing machine for paint films, the combination of a frame, a plurality of separate, independent arms pivoted on said frame, ball members mounted on the ends of said arms adapted to mar to different degrees the surface of a paint film, a plurality of pulleys mounted on said frame, a plurality of weights suspended from said pulleys and connected to the opposite ends of said arms serving to hold said ball members in lowered position, a cam member mounted on said frame adjacent the ends of said arms serving to raise the ball members against the force of said 30 weights, and means for supporting a paint film in predetermined relationship to said ball members.

35 3. In testing machine for paint films, the combination of a frame, a plurality of separate, independent arms pivoted on said frame, ball members mounted adjacent the ends of said arms adapted to mar to different degrees the surface of a paint film, a plurality of weights connected to the opposite ends of said arms serving to hold said ball members in film engaging position, a cam member mounted on said frame adjacent the ends of said arms adapted to raise the ball members against the force of said weights, parallel members mounted on said frame forming a track for a movable carriage, a movable carriage adapted to travel on said track, said carriage serving to support a paint film in predetermined relationship to said members, and means for moving said carriage beneath said 40 members while said members are in engagement with the paint film so as to mark to different degrees the surface of the paint film.

45 4. In a testing machine for paint films, the combination of a frame, a plurality of separate, independent arms pivoted on the frame, ball members mounted adjacent the ends of said arms adapted to mar to different degrees the surface of a paint film, a plurality of weights connected to the opposite ends of said arms serving to hold said ball members in film engaging position, a cam member mounted on said frame adjacent the ends of said arms adapted to raise the ball members against the force of said 50 weights, parallel members mounted on said frame

frame forming a track for a movable carriage, a movable carriage adapted to travel on said track, said carriage serving to support a paint film in predetermined relationship to said ball members, means for holding the paint film in fixed position on said carriage, and means for drawing said carriage on said track at a predetermined speed to move the paint film beneath said ball members.

5. In a testing machine for paint films, the combination of a frame, a plurality of separate, independent arms pivoted on said frame, ball members mounted adjacent the ends of said arms adapted to mar to different degrees the surface of a paint film, a plurality of pulleys mounted on said frame, a plurality of weights suspended from said pulleys and connected to

the opposite ends of said arms serving to hold said ball members in lowered position, a cam member mounted on said frame adjacent the ends of said arms adapted to raise the ball members against the force of said weights, parallel members mounted on said frame forming a track for a movable carriage, a movable carriage adapted to travel on said track, said carriage serving to support a paint film in predetermined relationship to said ball members, means for holding said paint film in fixed position on said carriage, and a motor mounted on said frame adapted to move said carriage on said track thereby advancing the supported paint film beneath said ball members.
